UNITED STATES PATENT OFFICE.

RALPH M. SHARAF, OF NEW YORK, N. Y., ASSIGNOR TO R. M. SHARAF MACHINE COMPANY, OF BOSTON, MASSACHUSETTS, A CORPORATION OF MASSACHUSETTS.

FEED MECHANISM FOR SEWING MACHINES.

Application filed May 4, 1921. Serial No. 466,718.

To all whom it may concern:

Be it known that I, RALPH M. SHARAF, a citizen of the United States, and resident of the borough of Bronx, county of Bronx, 5 city and State of New York, have invented certain new and useful Improvements in Feed Mechanism for Sewing Machines, of which the following is a specification.

This invention relates to an improved feed 10 mechanism for sewing machines and has particular relation to a two-needle zig zag sewing machine of that general construction which is fully described and claimed in my pending application for Letters Patent 15 Serial No. 92,141, filed April 19, 1916.

The subject matter of the present application primarily contemplates certain improvements in a feeding mechanism for machines of the character referred to, of that 20 type disclosed in a second application for patent filed by me on December 11, 1917, Serial No. 206,694. It is, however, to be understood that these improvements are not necessarily limited in their utility to application and use in connection with any 25 specific type of sewing machine, though they may perhaps find their greatest utility when employed in combination with the mechanism disclosed in my co-pending applications. 30

It is one of the important objects of the present invention to provide in a single dog type of feeding mechanism automatically acting means for at all times holding the 35 material against the underside of the vertically movable presser foot and to thereby insure exactly the required extent of feeding movement of the material in each operation of the feed mechanism for the proper 40 formation of the stitches.

The present invention further comprehends the provision of improved means for yieldably mounting the feed dog so that in the event that the material engaged by the 45 dog may be thicker at one point than at another, the dog in such event will automatically yield while maintaining a proper gripping action upon the material to insure its movement in the progressive formation 50 of the line of stitching.

With the above and other objects in view, the invention consists in the improved feed mechanism for sewing machines and in the

form, construction and arrangement of the several parts thereof, as will be hereinafter 55 more fully described, illustrated in the accompanying drawings and subsequently incorporated in the subjoined claims.

In the drawings, wherein I have disclosed one practical and satisfactory embodiment 60 of the invention and in which similar reference characters designate corresponding parts throughout the several views:

Figure 1 is a top plan view of the throat plate of a sewing machine, the feed dog being omitted; 65

Figure 2 is a vertical sectional view through the presser foot and the throat plate taken on the line 2—2 of Figure 1;

Figure 3 is a similar view, the throat 70 plate being partly broken away showing the feed dog in place with the operating means therefor illustrated in dotted lines;

Figure 4 is a transverse sectional view taken on the line 4—4 of Figure 3; 75

Figure 5 is a longitudinal section taken on the line 5—5 of Figure 3; and

Figure 6 is an enlarged sectional view of the feed dog.

Referring in detail to the drawings, 5 80 designates the throat plate of a sewing machine which is provided with spaced parallel longitudinally extending slots 6. The upper surface of the throat plate is also provided with longitudinal channels 7 communicating with the respective slots 6 at one of their ends. In these channels 7 the spring steel strips 8 are arranged, the outer ends of said strips being flush with the surface of the throat plate and rigidly fixed to 85 said plate by means of the screws 9. The underside of each of said spring metal strips is recessed as at 10 and the remaining portion of the metal strip extending inwardly from the recess is sprung upwardly 90 as at 11 and owing to the inherent resiliency of the metal is normally projected at its extremity above the upper surface of the throat plate. The inner opposed edges of these free end portions of the resilient metal 95 strips are obliquely inclined as at 12, said inclined edges overlying the slots 6. With these inclined edges 12 of the metal strips 8 the movable material folding members 13 co-operate. 100

The folders 13 are carried by the presser-

foot 14 which is mounted upon the lower end of a vertically reciprocating rod

spring 30 will move as a unit therewith in relation to the fixed stud bolt 25.

15. The particular construction of this

presser-foot and the operating mechanism 5 for the folders 13 is fully described and claimed in my co-pending application for patent, Serial No. 233,471, filed May 9, 1918, and since it forms no essential part of the present invention, need not be herein further described in detail. For the purpose 10 of the present explanation it will suffice to state that the spaced needles 16 of the sewing machine operate through the presser-foot and the slots 6 of the throat plate and 15 are vibrated transversely in the guide loops 18 formed on the end of the arm 17 fixed to the underside of the throat plate.

Adjacent to each of the slots 6 and in longitudinal alignment therewith the openings 19 are formed in the throat plate. Beneath these openings the longitudinally movable feed dog is mounted. As herein shown, I preferably form this dog from a metal plate having spaced parallel portions 20 the upper surfaces of which are toothed or corrugated as at 21, the said portions of the feed dog engaging through the respective openings 19 in the throat plate. The portions 20 of the feed dog are integral- 25 ly connected with each other by means of the ears 22 which extend at right angles to the portions 20 and are pivotally mounted as at 23 upon an oscillatable head 24 arranged upon the upper end of a fixed stud 30 bolt 25 carried by the longitudinally shift- 35 able yoke 26. The pivots 23 of the feed dog extend substantially in line with the yoke 26. The operating mechanism for oscillat- 40 ing the head 24 carrying the feed dog in a horizontal plane is indicated at 27 and is fully described and claimed in my co-pending patent application, Serial No. 206,694 above referred to. As also disclosed in said 45 application the yoke 26 is longitudinally reciprocated to feed the work by a crank arm 28 and is vertically moved to project the feed dog through the openings 19 by means of a second arm 29 which co-acts with the yoke 26. From the foregoing it will be 50 understood that the feed dog comprising the portions 20 is mounted to oscillate in a direction at right angles to the line of movement of the material.

The feed dog is normally yieldingly supported against pivotal movement upon the head 24 with the portions 20 of the dog in parallel relation to said head by means of a bowed leaf spring 30, the central portion of which is pivotally engaged upon a pin 31 55 fixed in the head of the bolt 25. The extremities of this leaf spring respectively bear against the undersides of the spaced portions 20 of the dog. It will be apparent 60 that in the horizontal oscillating movement 65 of the head 24 the dog and its supporting

In the operation of the mechanism as

above described, it will be understood that 70 the material is drawn over the surface of the throat plate and over the upwardly projecting end portions of the spring metal strips 8 between said strips and the presser- foot 14. These strips of spring metal serve to at all times hold the material closely 75 against the underside of the presser-foot and when the presser-foot descends the upwardly projecting ends of the spring metal strips are forced downwardly and placed under greater tension. Thus the material 80 is securely held when the feed dog is in lowered position. In the feeding operation, the dog is moved upwardly so that the portions 20 thereof are projected through the 85 openings 19 in the throat plate and the teeth or corrugations 21 are caused to grip the material. In this gripping action of the feed dog and during its longitudinal movement to feed the material longitudinally over the throat plate, said material is still 90 closely held against the underside of the presser-foot. By reason of the provision of the resilient metal strips 8, the material is fed very accurately to the precise extent 95 necessary in order that the stitches may be 100 properly formed.

As shown in Figure 4 of the drawings, should the material along one of the lines of stitching be of greater thickness than along the other line of stitching, the feed dog will readily yield against the holding action of the leaf spring 30, said dog rocking upon the pivots 23. It will thus be apparent that both of the parts 20 of the feed dog will in this manner be maintained in 105 gripping contact with the material so that the material along both lines of stitching will be fed precisely to the same extent in each operation of the feeding mechanism.

From the foregoing description, considered in connection with the accompanying drawings, the construction, manner of operation and several advantages of the present invention will be clearly understood. I have found that the improvements herein disclosed though of a very simple character 115 greatly increase the accuracy of the sewing operation as performed by the mechanism disclosed in my prior applications. By the provision of the resilient holding means for the material and the improved mounting of the feed dog, unavoidable contingencies which may affect the uninterrupted continuity of the sewing operation will be automatically compensated for.

I have herein disclosed what I consider a preferable embodiment of the present improvements, but it will of course be understood, that the invention might also be incorporated in various other alternative 130

structures and I accordingly reserve the privilege of adopting all such legitimate changes in the form, construction and relative arrangement of the several elements 5 as may be fairly embodied within the spirit and scope of the invention as claimed.

I claim:

1. In a sewing machine, the combination with a throat plate having a groove in its 10 upper surface and a presser foot, of a leaf spring mounted in said groove for yieldingly holding the material against the underside of the presser foot in all positions of the latter, and means for feeding the material against the retarding action of said 15 spring.

2. In combination with the throat plate, presser foot and needle of a sewing machine, a spring element fixed to the throat plate 20 and having a free end portion normally projecting above the surface of the throat plate and acting to yieldingly hold the material against the underside of the presser foot, said spring element being formed at its free 25 end portion with an inclined edge converging with relation to the other edge of the element to a point adjacent to the path of movement of the needle and said free end portion of the element being arranged to be 30 depressed into the plane of the throat plate upon the downward movement of the presser foot, means for feeding the material against the retarding action of said spring when the presser foot is raised and means co-operating 35 with the inclined edge of said element to fold the edge of the material.

3. In combination with the throat plate and presser foot of a two-needle sewing machine, spring metal strips fixed at one of 40 their ends in the throat plate, the other ends of said strips normally projecting above the surface of the throat plate and yieldingly engaging the material along the respective seam lines thereof to hold the material 45 against the underside of the presser foot, said spring strips being depressed into the plane of the throat plate in the downward movement of the presser foot, and means for feeding the material against the retarding 50 action of said spring strips when the presser foot is raised.

4. In a feed mechanism for two-needle sewing machines, a feed dog having integral spaced portions to grip the material along 55 the respective lines of stitching, and means for mounting said dog whereby the spaced portions thereof may be automatically varied to accommodate themselves by variations in thickness of the material.

5. In a feed mechanism for two-needle sewing machines, a feed dog mounted to oscillate in a direction at right angles to the line of movement of the material and having rigidly connected spaced portions to grip

the material along the respective lines of 65 stitching, and means for yieldingly resisting the oscillating movement of the feed dog and permitting the spaced portions of the dog to automatically accommodate themselves to variations in thickness of the material. 70

6. In a feed mechanism for two-needle sewing machines, a feed dog pivotally mounted for oscillatory movement in a direction at right angles to the line of movement of the material and having rigidly connected spaced portions to grip the material along the respective lines of stitching, and a spring co-acting with the spaced portions of the dog and yieldingly resisting such oscillating movement, while permitting said spaced portions to automatically accommodate themselves to variations in thickness of the material. 75

7. In a feed mechanism for two-needle sewing machines, a longitudinally reciprocating head mounted to oscillate upon a vertical axis, a feed dog pivotally mounted upon said head for oscillatory movement with respect thereto in a direction at right angles to the line of movement of the material, said dog having rigidly connected spaced portions to grip the material along the respective lines of stitching, and means yieldingly resisting such independent oscillating movement of the feed dog while permitting the spaced portions thereof to automatically accommodate themselves to variations in thickness of the material. 80

8. In a feed mechanism for two-needle sewing machines, a longitudinally reciprocating head mounted to oscillate upon a vertical axis, a feed dog pivotally mounted upon said head for oscillatory movement with respect thereto in a direction at right angles to the line of movement of the material, said dog having rigidly connected spaced portions to grip the material along the respective lines of stitching, and a leaf spring engaged at its ends with the spaced parts of the feed dog and movable as a unit with said dog and the head in the oscillation of the latter, said spring yieldingly resisting the independent oscillating movement of the dog while permitting the spaced portions thereof to automatically accommodate themselves to variations in thickness of the material. 100

9. In a feed mechanism for two-needle sewing machines, an oscillating feed dog 110 having rigidly connected portions at opposite sides of its center of oscillation to grip the material along the respective lines of stitching, and means for resisting the oscillating movement of the feed dog and permitting the spaced portions of the dog to automatically accommodate themselves to variations in thickness of the material. 120

10. In a feed mechanism for two-needle sewing machines, an oscillating feed dog having integral gripping portions on each side of its pivotal connection and means for resisting the oscillating movement of the feed dog and permitting the spaced portions of the dog to automatically accommodate themselves to variations in thickness of the material.
- In testimony that I claim the foregoing as my invention, I have signed my name hereunder:

RALPH M. SHARAF.
